UNITED STATES PATENT OFFICE.

WILLIAM WALLACE DICKINSON, JR., OF LITTLE ROCK, ARKANSAS.

APPARATUS FOR BURNING BRICK.

1,305,447.

Specification of Letters Patent.

Patented June 3, 1919.

Application filed March 18, 1918. Serial No. 223,026.

To all whom it may concern:

Be it known that I, WILLIAM WALLACE DICKINSON, Jr., citizen of the United States, residing at Little Rock, in the county of 5 Pulaski and State of Arkansas, have invented a certain new and useful Improvement in Apparatus for Burning Brick, of which the following is a full, clear, and exact description, reference being had to the 10 accompanying drawings.

This invention relates to the burning of brick and has for its general object the provision of a new and simplified apparatus for the performance of such burning whereby 15 the amount of permanent construction is decreased, whereby heat is conserved, and whereby the employment of inclosed structures is avoided, thus permitting the building and demolition of the kilns by means of 20 labor-saving transporting devices.

While fuel and labor were cheap, kilns were ordinarily built in the form of loosely piled rectangular masses of brick having spaced archways at the bottom and having 25 their tops nearly or substantially naked, so that the hot combustion gases rose freely therethrough and escaped. Later, with the increase in the price of fuel, numerous attempts have been made to utilize 30 the gases in a plurality of kilns successively, but so far as I am aware this has been effected only by the employment of closed permanent chambers having comparatively 35 small openings or doorways through which it is necessary to transport the brick before and after burning. Also the only successful arrangements of this nature so far developed, so far as I have been able to learn, have been those in which the hot gases were 40 delivered to the upper part of such permanent chambers and withdrawn from the bottom. Such permanent chambers are generally built of firebrick and are always extremely expensive, and of comparatively 45 short life; owing to the heat retention of their walls, much time is lost after burning in waiting for them to cool so that workmen can enter and remove the bricks; they are stifling and unpleasant to work in, particularly in hot weather; all the bricks have 50 to be transported and set by hand, since nothing larger than a wheelbarrow can be gotten into or out of the openings; the investment is so great that it is necessary to 55 keep it in use at all times, wherefore the bricks must necessarily be removed as soon

as possible after burning, in order that a succeeding burning may take place, and if there be no immediate market for those bricks they must be sent to a storage yard, 60 thus necessitating a separate handling; the down-draft system is unscientific and unnatural, difficult to operate and has a tendency to water-log the lowermost bricks of each kiln; while the down-draft system requires that the entire floor of the kiln be 65 pervious to such gases, thus entailing very extensive underground constructions.

The objects of my invention are the provision of a construction of kilns such that no 70 above-ground permanent construction is employed; the provision of an apparatus whereby the permanent underground work is reduced to a minimum and is entirely removed from underneath the kilns; the provision of an apparatus wherein up-draft burning is employed at all times and wherein the spent gases from one kiln are conveyed to the next succeeding kiln; the provision of a system of kilns which can be 80 built by mechanical setters and demolished from the outside and sold without sorting; the provision of kiln structures containing a larger proportion of unburned brick than heretofore; the provision of kiln structures 85 of such cheapness as to permit the burned bricks to be stored economically in the original kilns, thereby avoiding one handling; the provision of apparatus whereby the kilns can be burned with less fuel, time and 90 labor than heretofore; while further objects and advantages of the invention will become apparent as the description proceeds.

In the drawings accompanying and forming a part of this application I have shown 95 certain preferred embodiments of my said invention, although it will be understood that the same constitute only a few of a greater number which may be employed for the purpose in view within the scope of my 100 invention. In these drawings Figure 1 represents diagrammatically a plan view of my improved burning shed or yard, the roof being omitted; Fig. 2 represents a side elevation of the same; Fig. 3 is a transverse sectional view upon the broken line 3—3 of Fig. 1 and drawn to an enlarged scale; Figs. 4, 5 and 6 are sectional views taken upon the lines 4—4, 5—5, and 6—6 respectively of Fig. 1 and drawn to a yet larger scale; Fig. 110 7 is a top plan view of one section of kilns, partly broken away so as to show the ar-

angement of bricks; while Fig. 8 is a dia-
grammatic view showing a modified ar-
rangement.

Fig. 9 is a horizontal sectional view
5 through a modified arrangement correspond-
ing approximately to the line 9—9 of Fig.
10; Fig. 10 is a vertical sectional view of
the modification showing line 9 taken upon
the line 10—10 of Fig. 9; Fig. 11 is a trans-
10 verse sectional view taken on the broken line
11—11 of Fig. 9; Fig. 12 is a longitudinal
sectional view of still another modification
corresponding to the line 12—12 of Fig. 13;
and Fig. 13 is a transverse section across the
15 modification shown in Fig. 12.

According to my invention I build a large
number of kilns in a row, adjacent kilns be-
ing separated by a narrow passageway de-
fined between impervious walls. Located
20 beneath each passageway is an underground
tunnel having a perforated roof establishing
continuous communication with said pass-
ageway. Other tunnels are provided out-
side of and parallel to the side walls of the
25 kilns whereby said first tunnels can be placed
in communication either with a succeeding
kiln or with an exhaust device; while the
top of each kiln is roofed over in such wise
as to place the same in communication with
30 its appropriate passageway while preventing
undue escape of the combustion products.
Said kilns are preferably arranged in two
rows so that the process may be made con-
tinuous without interruption and so that
35 the amount of permanent structure may be
correspondingly reduced; although many
changes in this and other details can be
made within the scope of my invention.

In the drawings A, B, C, D, E, * * *
40 P, Q, R, S, T, U, * * X, Y, Z represent the
kiln spaces which preferably consist merely
of hardened and leveled ground and have a
uniform standard size, for example from
thirty to forty feet square. I prefer to
45 have them square, since such construction
lends itself more readily to the employment
of mechanical setting devices, although this
is not essential, since my improvements are
of great value apart from the usability of
50 such devices. Adjacent kiln spaces are sepa-
rated by spaces some four or five feet wide,
and beneath these spaces are constructed the
tunnels 1^a, 1^b, 1^c, etc., (the number depend-
ing upon the number of kilns). Each of
55 these tunnels is formed with a top consist-
ing of spaced arches 2, 2 (Fig. 6) upon
which are laid the spaced bricks 3 substan-
tially flush with the surface of the ground.
Outside of the kiln spaces are provided the
60 longitudinal tunnels 5, 5 with which the tun-
nels 1^a, 1^b, 1^c, etc., communicate freely. The
last named tunnels are divided by partitions
6, 6 into sections, each of which sections are
provided with one or more upwardly open-
65 ing apertures 7 and 8, whose use will be ex-

plained later. Outside of and parallel to the
tunnels 5, 5 other tunnels are provided as
shown at 9, 9, and 10, the tunnel 10 being
located between the two rows of kilns so as
to serve both of them in a case where a 70
double row of kilns is employed.

The preferable construction of each kiln
is as follows: Along each side of the kiln-
row parallel to and inside of the longitudinal
tunnels 5, 5 is erected a continuous wall 12 75
of unburned bricks, preferably mixed with
carbon, sawdust, or other burnable material
as well understood by brick makers; and
connecting these walls are the transverse
walls, 13, 13^a, 14, 14^b, 15, 15^c, etc., also of 80
unburned brick preferably containing car-
bon. The walls 13^a and 14, 14^b and 15, 15^c
and 16 are located upon opposite sides of 85
the transverse tunnels 1^a, 1^b, 1^c, etc., respec-
tively, so as to define the vertical passage-
ways, a, b, c, etc. The walls 13, 14, 15, etc.,
are extended to a height level with the walls
12, 12 while the walls 13^a, 14^b, 15^c, etc., ter-
minate at a lower level (preferably about 90
six to eight courses of brick, so as to afford
communication between the kilns and their
respective passageways). The body of each
kiln is filled with unburned, carbon-free
brick, shown at 19, the loose regular modes
well understood by bricklayers up to the top
95 of the walls 13^a, 14^b, 15^c, leaving, however,
the eyes or archways 20, 20 which also extend
outward through the walls 12, 12. Above
the level defined by the shorter walls are
laid the requisite number of courses of car-
bon-brick shown at 21, also loosely arranged,
100 to fill the kilns to a level with the top of the
walls 12, after which the top of the kiln is
covered with a plating 22 of burned brick,
preferably about three courses deep. The 105
sides and ends of the kiln row are also in-
cased in a scove casing 23 of burned brick,
also laid up close except where pierced by
the eyes of arches 20, and both top and sides
are finally daubed with clay to prevent gas 110
leakage.

The passageways a, b, c are also prefer-
ably filled with unburned brick, loosely piled
so as to permit the flow of gases there-
through, this brick also preferably 115
mixed with carbon or sawdust.

The apertures 7—7 are arranged, one op-
posite each of the eyes or arches 20 so as
to permit the reception of the sheet metal
elbows 30, 30 as shown in Figs. 3, 5 and 7, 120
the ends of the arches being filled with
rubble walls 31, 31 around the ends of these
elbows.

The tunnels 9, 9 and 10 are formed with
upwardly opening apertures 32, one opposite 125
each of the apertures 8, so as to permit the
reception of the sheet metal return fittings 33,
33 whereby the last mentioned tunnels can
be placed in communication with the desired
sections of the tunnel 5, 5. Suitable covers 130

34, 34 are provided for closing the apertures 7, 7 after the removal of the elbows 30, and other covers 35 are provided for closing the apertures 8 and 32 upon the removal of the 5 fittings 33. In case a single exhaust tunnel 10 is employed to serve two adjacent tunnels 5, 5, as shown herein, the same is preferably located half way therebetween and formed with spaced branches 36, 36 leading to the 10 connecting tunnels which it serves. Each of the elbows 30, 30 is preferably provided with a suitable damper 37 whereby the flow of gas therethrough can be regulated. The tunnels 9, 9 and 10 are preferably all connected 15 together as shown at 40 (so as to cause the suction therein to be equal under all conditions) and thence to a suitable suction device 41, here shown as an exhaust fan. Also in the case of a two-row arrangement such as shown in Figs. 1 to 6, the end 20 kiln of each row has its draft passage communicating by way of a transverse tunnel 43, with the connecting tunnel 5, 5 of the opposite row, so that the operation may be 25 made continuous.

That operation is as follows:—

Assuming that the kilns A, B, C, D and E have been completely built as heretofore described, and the apparatus is to be used 30 for the first time; the heat is applied to the eyes or arches of kiln A in any suitable or approved manner, preferably by gas or oil-flame-injection; simultaneously the transverse passage 1^a is connected, by means of 35 the return-bends 33, 33 with the exhaust tunnels 9, 10, and the suction device 41 set in operation, all of the apertures 7, and all the other apertures 8 being meanwhile closed by their respective covers. As a consequence 40 the heated gases are aspirated through all the brick work of the interior of the kiln A, and downwardly through the passage a. As soon as this kiln has dried out so as to diminish the vapor content of the issuing 45 gases to the proper degree and to permit the temperature of those gases to rise slightly, the apertures 7 opposite kiln B are provided with elbows 30, 30 and the return bends 33 are shifted to the apertures 8 which lie 50 opposite the ends of tunnel 1^b, the apertures from which those bends were removed being closed by their appropriate covers 35. The gases from the kiln A now pass downwardly 55 as before through passageway A into tunnel 1^a, thence via connecting tunnels 5, 5, and elbows 30, 30 into kiln B, thence downwardly through passageway b, thence via bends 33, 33 into tunnels 9, 10, and so to the exhaust device, 41.

60 As soon as kiln B has become heated to such an extent that the vapors issuing therefrom are not saturated, elbows 30—30 are applied to the arches of kiln C so as to connect the same to the tunnel section 5—5 adjacent thereto, and the fittings 33 are moved

to a point opposite the tunnels 1^c, the apertures opposite the tunnel 1^b being now closed with their covers; and similarly when kiln C has become partially dried out, kiln D is connected in series therewith in the same 70 manner. The effect of the firing of kiln A is thus transmitted to the three succeeding kilns, which is the largest number that I apprehend can safely be treated at one time; although I appreciate that with some kinds 75 of clay it will be inadvisable to operate so many series, and with other kinds of clay it may be possible to link together a still larger number.

Each kiln requires approximately two 80 days for complete burning of the brick, and upon the completion of any one kiln, the heating agent is applied to the next kiln in the series, and the elbows thus released are transferred to the next kiln which has not 85 yet been dried. The fact that all of the tunnels are under suction instead of being under pressure, permits the removal of any elbow or cover, and the substitution of some other element therefor without danger of 90 annoyance by reason of the escape of heated gases.

As soon as each kiln has been burned it is left to cool and can be torn down as soon or late as desired; the amount of permanent 95 structure for each kiln comprises only a few small tunnels, none of which are underneath the kiln itself, and of which the value is so small compared with the value of the kiln itself as to permit the bricks to be left 100 *in situ* economically until required. Upon demolishing the kiln, all of the bricks taken therefrom, being of the same quality throughout, both top, sides and interior, can be sold for one price and without sorting. 105 Also being demolished from the outside, they can be removed by mechanical means, such as brick hoists and traveling cranes.

In the case of the two row arrangement shown in Figs. 1 and 3 hereof, the burning 110 proceeds up one row and down the other, and it is possible to jump across from one row to another at any point desired by means of suitable cross-over fittings, in case it is not desired to utilize the entire extent 115 of the kiln-row, or in case a part of the same be occupied with the storage kilns.

In some cases it may be preferable to employ the one row arrangement as is shown in part in Fig. 8 hereof, wherein A', B', and C' represent kiln-spaces. In this case the tunnels 5^a—5^a need extend only to the end of kiln B', and the tunnels 9^a—9^a need extend only as far as kiln C', suitable apertures 8^a—8^a being provided as shown in Fig. 125 8; whereby the nearest tunnel sections can be connected together by return bends as already described. Also the tunnels 9^a—9^a may be connected to independent exhaust devices 41^a—41^a if desired rather than to a 130

single device. It will be understood that the straightaway arrangement shown in Fig. 8 is exactly as good as the continuous, or end-less-chain arrangement shown in Fig. 1, 5 until the last kilns of the series are reached; and the only drawback even then resides in the fact that the heat from the last two or three kilns is wasted and more time and trouble are required to start the burning 10 anew.

The metal elbows and fittings are not essential to the invention since it is clear that their purpose will equally be served by means of extensions of the tunnels either 15 below or above ground and communicating with the kiln or with each other either inside or outside the line of the walls, the openings being governed either by removal covers or by sliding or swinging dampers or doors. 20 In Figs. 1 to 8 inclusive I have shown the tunnels as outside the line of the kilns so as to lessen the weight thereon and permit cheaper constructions. In Figs. 9, 10 and 11 I have illustrated a modification of my invention wherein the tunnels 5^a are located 25 inside of and underneath the kilns, their tops being formed with apertures 7^a—7^a registering with the arches 20—20 and also with other apertures 8^a—8^a registering with other 30 arches 50—50 formed, one in each of the down draft passageways. Each of the openings 7^a and 8^a is governed by means of a suitable damper, such as a sliding plate, operated by a handle 51 projecting outside of 35 the kiln. The tunnel 5^a is also provided with partitions 6 substantially registering with the shorter wall which divides each passageway from its respective kiln.

The tunnels 9^a 9^a are here shown as located 40 comparatively close to the kiln walls and as communicating with the respective tunnels 5^a 5^a by means of transverse passages 52 52 adjacent to the openings 8^a, the last named passageways being governed by 45 sliding dampers 53 operated by handles 54 projecting above the ground.

This arrangement dispenses with the necessity of all metal fittings and places the tunnels in direct communication with the 50 kiln. I have shown eyes or arches 50 inside the different passageways the better to distribute the suction over the entire area of the same; and in fact the entire passageway could be left empty of brick within the scope 55 of my invention, although the presence of a brick filling is highly desirable to support the walls thereof against bulging and the roof of the kiln from falling.

In Figs. 12 and 13 I have shown yet another 60 embodiment of my invention wherein only a single tunnel is used. This tunnel is desirably of circular shape and is preferably located underneath the center line of the kilns as shown at 60—60. One end of 65 it is closed at 61, and the opposite end is

connected to the suction device, not shown. The upper wall of this single tunnel is formed with spaced apertures 7^b 7^b registering with the eyes or arches 20 20 and also with apertures 8^b 8^b registering with arches 50 50 formed in the down draft passageways. Between each aperture 8^b and the nearest aperture 7^b of the kiln whose down draft passageway it serves is located a large size damper or shutter 61 suitably connected 75 to a crank or handle 62 located at one side of the kiln. If any damper be closed the gases will be forced to rise through the kiln and descend through the downdraft passage, while if any damper be open, the lower resistance of the direct passage will prevent the occurrence of any appreciable flow. Thus if it is desired to burn the kiln A', the heat is applied to the arches 20 20 in the usual manner, the burned gases passing upwardly through the bricks and down through 85 the passageway through the aperture 8^b, the corresponding damper 61 being closed; and if it is desired to dry the kiln B' with the waste heat it is necessary merely to close 90 this damper when the gases will be forced to rise through the apertures 7^a thereof and descend through the corresponding apertures 8^b; while if it be not desired to apply 95 this waste heat to kiln C' it is necessary merely to open that damper, permitting the heated vapor to flow directly through the exhaust.

It will be understood that many further modifications and changes can be made within 100 the scope of my invention and to all of these I lay claim except such as may be specifically excluded by the language of the claims hereto annexed.

My invention can be applied either to a 105 large or small number of kilns; it is advantageous in even a small plant but affords its maximum advantage only when employed to an extent of about forty or more units. It will be understood that each kiln requires 110 about two days to burn during which time the two or three preceding kilns are cooling and the two or three succeeding kilns are "water smoking". It is very desirable that there be at least two or three kilns in advance 115 of these last settling and drying out (which operation can easily be helped by connecting their draft passageways to the suction tunnels and drawing air slowly through them). Then it is generally most convenient 120 to build several kilns together so as to afford greater stability and also to avoid crowding the workmen; it is desirable for the same reason to dismantle several kilns simultaneously; it is generally necessary to maintain 125 a cleared space of at least a few areas ahead of the builders; it is generally desirable to have a few kilns of burned brick on hand as storage; and it must be remembered that burning continues every day in the year 130

while building takes place only on working days and subject to the ability to secure laborers. Therefore, while my improvements are perfectly operative on two kilns and even 5 thus affords advantages hitherto unattained, yet this advantage grows with size of plant.

Having thus described my invention, what I claim is:—

1. In combination a plurality of brick 10 kilns each having its interior part of bricks loosely piled, and having its top and sides formed of bricks closely piled, one of the sides of each kiln being formed with a vertical passageway which communicates at its 15 upper end with the interior of said kiln adjacent to its top, and at its lower end with a conduit leading to the lower part of a succeeding kiln.
2. In combination, a plurality of brick 20 kilns built in a row, successive kilns being spaced apart to define vertical passageways, the upper end of each passageway communicating only with the kiln at one side of itself and the lower end of each passageway 25 adapted to be connected either to the succeeding kiln or to a suction device.
3. A brick kiln built of loosely piled bricks incased at its top and sides with closely laid bricks, the lower part of said 30 kiln being formed with arches or eyes, a pair of spaced walls of closely laid brick located at the end of said kiln and defining a passageway which communicates with the interior of said kiln at an elevated level 35 thereof immediately beneath its top incasement, and means whereby the lower end of said passageway may be connected with the eyes or arches of a succeeding kiln.
4. In a structure of the character described, a mass of loosely piled bricks constituting the body of a kiln, a plurality of side walls of closely piled bricks laid thereagainst, a top of closely piled bricks laid upon said first mass, one of said side walls 45 terminating at a point below said top and the remainder extending to said top, a wall of closely laid brick spaced from said shorter wall to define therewith a passageway which communicates with the interior 50 of said kiln over the top of said shorter wall, and connections for exhausting gases from the lower end of said passageway.

5. In a structure of the character described, a mass of loosely piled bricks constituting the body of a kiln, a plurality of side walls of closely piled bricks laid thereagainst, a top of closely piled bricks laid upon said first mass, one of said side walls terminating at a point below said top and 55 the remainder extending to said top, a second kiln spaced from the first kiln having similar higher and lower walls one of the higher walls of the second being spaced from the lower wall of said first kiln to define a passageway, and means whereby the 60

lower end of said passageway can be placed in communication with the interior of the second kiln.

6. In brick burning apparatus, a plurality of rectangular masses of loosely piled 70 bricks constituting the bodies of kilns, each of said masses being incased by side- and top-walls of closely laid brick, the end walls of adjacent kilns being spaced apart to provide vertical passageways, both side 75 walls and one end wall of each kiln extending into conjunction with the top wall and the remaining end wall of each kiln terminating short of the top wall so as to permit communication between said passageway 80 and the kiln interior.

7. In brick burning apparatus, a plurality of rectangular masses of loosely piled 85 bricks constituting the bodies of kilns, each of said masses being incased by side- and top-walls of closely laid brick, the end walls of adjacent kilns being spaced apart to provide vertical passageways, both side 90 walls and one end wall of each kiln extending into conjunction with the top wall and the remaining end wall of each kiln terminating short of the top wall so as to permit communication between said passageway 95 and the kiln interior, an opening communicating with each of said passageways and means for connecting said opening either to a suction device or to the interior of another kiln.

8. In brick burning apparatus, a plurality of rectangular masses of loosely piled bricks 100 constituting the bodies of kilns, each of said masses being incased by side- and top-walls of closely laid brick, the end walls of adjacent kilns being spaced apart to provide vertical passageways, both side walls 105 and one end wall of each kiln extending into conjunction with the top wall and the remaining end wall of each kiln terminating short of the top wall so as to permit communication between said passageway and 110 the kiln interior, the interior of said passageway being filled with loosely piled bricks which support the end and top walls, and means for connecting the lower end of said passageway either to a suction device or 115 to another kiln.

9. In brick burning apparatus, in combination, a pair of parallel side walls of closely laid brick, a plurality of transverse walls also of closely laid brick traversing the 120 space between said side walls and defining alternate wide and narrow areas, each wide area constituting a kiln and each narrow area a passageway, the wall between each kiln and one passageway terminating at a 125 lower level than the other walls, loosely piled brick located in both said wide and narrow areas and extending substantially to the top of said higher walls, a top of closely laid brick covering the entire structure and 130

- joined to said higher walls, and means whereby the lower end of each passageway can be connected either to a suction device or to another kiln.
- 5 10. In brick burning apparatus, in combination a pair of spaced tunnels, a plurality of transverse tunnels connecting the same and coöperative therewith to define kiln spaces, the tops of said last tunnels being of 60
10 a foraminous construction, means separating said first tunnels into sections, one for each kiln space, a suction device, and means for connecting any one of said tunnel sections selectively to said suction device.
- 15 11. In brick burning apparatus, in combination, a pair of spaced tunnels, each tunnel having a plurality of spaced apertures opening through the ground surface, kilns located between said tunnels and having eyes 70
20 or arches adjacent said tunnels, transverse tunnels located between adjacent kilns, and communicating with said first tunnels, a brick passageway establishing communication 75
25 between the top of each kiln and one of said transverse tunnels, a suction device, means whereby certain of said apertures can be placed in communication with said eyes, and means whereby other apertures can be connected to said suction device.
- 30 12. In brick burning apparatus, in combination, a pair of spaced tunnels, a plurality of transverse tunnels connecting the same at spaced points, a partition traversing each 80
35 of said first tunnels between adjacent transverse tunnels, kilns having pervious centers and impervious walls, the last located near to and parallel with said tunnels, adjacent kilns being spaced apart and located upon opposite sides of said transverse tunnels 85
40 whereby to form passageways communicating with those tunnels, the upper end of each passageway communicating with one 90
45 of said kilns, a suction device, means for connecting any one of the first tunnel sections to said suction device, and means for connecting any of said sections to the interior 95
50 of the kiln to which it is adjacent.
13. In brick burning apparatus, in combination, a pair of spaced tunnels, a pair of 100
55 impervious walls parallel and near to said tunnels, a plurality of transverse walls connecting said first walls and spaced alternately farther and nearer to define wide and narrow spaces respectively, the wider spaces 105
55 being filled with loosely piled bricks and forming kilns, the narrower spaces filled
- with loosely piled bricks and forming passageways, the wall at one side of each passageway being lower than the other wall to establish communication with the kiln, 60
means establishing communication between each tunnel and the lower end of said passageway, means for establishing communication between each tunnel and the interior of each kiln adjacent thereto, a partition 65
across each tunnel at a point near said lower wall and dividing each tunnel into sections, and a suction device adapted to have any section connected thereto.
14. In brick burning apparatus, in combination, a tunnel having spaced openings, a plurality of updraft brick kilns spaced along said tunnel and having arches registering with said openings, successive kilns being spaced apart to provide downdraft passageways and said tunnels also having openings 70
75 communicating with said passageways, said kilns and passageways being incased by impervious walls, means for controlling the flow of gases through said first openings, a 80
85 suction device, and means for connecting said suction device in communicating relation with any one of said last openings.
15. In brick burning apparatus, the combination, with a tunnel of a plurality of updraft brick kiln ranges along said tunnels, the top and sides of each kiln being surrounded by an impervious casing, a wall 85
90 traversing each kiln transversely of said tunnel and terminating at a point adjacent to but spaced from its top whereby a down-draft passage is provided, means in said tunnel in substantial alinement with said wall for obstructing the flow of gases therethrough, there being openings between said 95
95 tunnel and kiln on each side of said wall, and means for aspirating gases from said tunnel.
16. The process of making burned bricks which contains the steps of building the dried unburned bricks into a series of loose piles, surrounding all said piles with a casing of burned bricks from a previous burning, applying heat to the interior of each pile in succession, conveying the waste heat 100
105 from the top of each pile to the bottom of a succeeding pile, allowing each pile to cool after burning, and finally demolishing said pile from the outside.
- In testimony whereof I hereunto affix my 110
signature.
- WILLIAM WALLACE DICKINSON, JR.
